(57) **CLAIM**

The ornamental design for a root-pruning mesh pot for plants, as shown and described.

DESCRIPTION

FIG. 1 is a top view of root-pruning mesh pot for plants showing my new design;

FIG. 2 is a side elevation view thereof;

FIG. 3 is bottom perspective view thereof;

FIG. 4 is top perspective view thereof;

FIG. 5 is a top plan view defining cross sectional plane 6-6; FIG. 6 is a cross-sectional view taken from lines 6-6 in FIG. 6;

FIG. 7 is a side elevation view defining cross-sectional planes 8-8 and 9-9;

FIG. 8 is a cross-sectional view taken from lines 8-8 in FIG. 7;

FIG. 9 is an enlarged view of area "9" of FIG. 8;

FIG. 10 is a cross-sectional view taken from lines 10-10 in FIG. 7;

FIG. 11 is an enlarged view of area "11" of FIG. 10; and, FIG. 12 is a cut-away view thereof.
